UNITED STATES PATENT OFFICE.

WILLIAM S. CHAMBERS, OF COEUR D'ALENE, IDAHO.

SEED-TREATING APPARATUS.

1,293,034.

Specification of Letters Patent. Patented Feb. 4, 1919.

Application filed February 11, 1918. Serial No. 216,589.

To all whom it may concern:

Be it known that I, WILLIAM S. CHAMBERS, a citizen of the United States, residing at Coeur d'Alene, in the county of Kootenai and State of Idaho, have invented certain new and useful Improvements in Seed-Treating Apparatus, of which the following is a specification.

The present invention relates to new and useful improvements in seed treating apparatus, and the primary object is to provide a device for treating grain seed, such as wheat, oats and the like, whereby to eliminate the smut germ from the grain.

There are numerous devices for this purpose, but my object is to provide a device which is simple in construction, inexpensive to manufacture, and one which will be more efficient in every respect than previous grain treating devices.

One object of the invention is to provide a device by which it will be possible to use a minimum quantity of treating fluid, but at the same time efficiently and effectually treat the grain to rid same of the smut germ that is contained in much wheat available, especially in certain parts of the country.

With this and other objects in view my invention consists generally in the various constructions and combinations as herein-after are more particularly described and pointed out in the specification and claims.

In the accompanying drawing forming a part of this specification—

Figure 1 is an elevation partly in section of the device constructed in accordance with my invention.

Fig. 2 is a cross section therethrough taken upon the lines 2—2 of Fig. 1.

Fig. 3 is a perspective view of the feed reservoir and brush which places the fluid in contact with the grain.

In describing the invention I shall refer to the drawings in which similar reference characters designate corresponding parts throughout the several views, and in which 10 designates the cylindrical casing or housing, 11 a suitable base for maintaining same in an upright position. Near one end of the 15 housing, which will be termed the feed end, is located and attached a hopper 12 provided with a valve 13 for regulating the supply of grain to the casing 10. Mounted within the casing upon suitable journals on the ends 20 thereof, I provide a spiral conveyer 14 and upon one end thereof extending outside the

casing a crank member 15 with the handle 16 for rotating or revolving said conveyer. Arranged immediately adjacent the hopper 12 I provide a housing 17 upon the upper 60 portion of the casing 10 of suitable dimensions to take care of a fluid feed member 18 and provide on said housing a hand screw or locking means 19 for fixedly positioning the member 18 and maintaining same in the 65 proper adjustment.

The feed device, here illustrated at 18, consists of a reservoir 19 supporting brush members 20 which may be of steel wire or bristles and the formation of this brush is 70 made to conform somewhat to the curvature of the conveyer flight within the casing. Upon the bottom of the reservoir 19 are numerous apertures 21 which allow the liquid to issue therethrough, drop by drop, 75 and be conveyed along the brush bristles to the ends thereof. Communicating with this reservoir is a supply hose or pipe 22 extending to a tank 23 and provided with a valve 24 for feeding the proper quantity of fluid 80 to the treating mechanism.

In treating grain such as wheat to remove the smut germ, it is necessary that the grain be immersed in or coated with a supply of a germicide such as vitriol which, 85 for convenience, is provided in liquid form and which will have the tendency on contact with the grain to kill the germ and render the grain free of that fungus growth known as "smut." At the same time it is necessary 90 to carefully treat the grain to prevent destruction of the seed germ which is frequently accomplished by too strong a treatment, or a treatment carried over too great a period of time. To provide a nicety of balance in this treatment and to conserve the supply of treating material which is rather expensive, the present device has been constructed and the operation of same is as follows:

When grain is fed through the hopper into the casing 10 and the spiral conveyer is rotated the grain will be propelled forward and the treating fluid will come in contact therewith by flowing from the ends 105 of the brush bristles. The bristles extending somewhat into the path of the spiral conveyer will be engaged by the outer edges of this conveyer and will be drawn backward at an angle and flipped as they pass 110 over the edge of the conveyer so that the fluid will be distributed over a considerable

area within the casing, much in the manner that a spray of a liquid may be thrown from a brush as it is swished through the air.

5 The action of the conveyer against the brush ends will thoroughly distribute the fluid over the grain and the action of the spiral conveyer as it passes the grain forward to the receiving end will cause the 10 seed to be rotated so that all parts of it will receive a supply of the treating fluid, but not a supply in excess to that which is desired and which is actually necessary for proper treatment. By regulating the speed 15 of the conveyer a proper treatment of the seed may be gained and if a greater or less quantity of fluid is required, manipulation of the valve 24 will provide the desired amount. Also by reason of the adjustable 20 fastening 19 the reservoir 18 and brush 20 may be so located as to provide proper and efficient distribution of the fluid.

It is sometimes desirable in treating seed grain that the solution be heated and when 25 so desired may be accomplished by heating the tank containing the fluid 23 or by heating before depositing in said tank.

From the foregoing description of the construction of my device the operation 30 thereof will be readily understood and while I have particularly described the elements best adapted to perform the function set forth, it is obvious that various

changes in form and proportion and in the minor details of construction may be resorted to without departing from the spirit or sacrificing any of the principles of the invention.

Having thus described my invention what I claim and desire to secure by Letters Pat- 40 ent is:—

1. The combination in a seed treating apparatus, a casing and its hopper and a spiral conveyer in the casing, a liquid feeding reservoir adjustably mounted on the 45 casing and having an apertured bottom communicating with the casing, brushes depending from the bottom into the casing and said brushes arranged transversely of the conveyer and conforming to the curvature 50 of said conveyer.

2. The combination in a seed treating apparatus, a casing and its hopper and a spiral conveyer in the casing, a housing mounted above the casing and a liquid feeding reservoir provided with an apertured bottom and adjustable in the housing, a set screw for holding the reservoir in adjusted position, and brushes depending from the bottom of the reservoir into the casing with their lower 60 ends arranged on a curved line conforming to the curvature of the conveyer for the purpose described.

In testimony whereof I affix my signature.

WILLIAM S. CHAMBERS.
